UNITED STATES PATENT OFFICE.

KRAFT BOOTH, OF PHILADELPHIA, PENNSYLVANIA, ASSIGNOR TO GILLINDER & SONS, INC., OF PHILADELPHIA, PENNSYLVANIA, A CORPORATION OF PENNSYLVANIA.

DESIGN FOR AN ARTIFICIAL-LIGHT SHADE.

No. 40,176.

Specification for Design.

Patented July 27, 1909.

Application filed May 27, 1909. Serial No. 498,775. Term of patent 14 years.

To all whom it may concern:

Be it known that I, KRAFT BOOTH, a citizen of the United States, and resident of the city and county of Philadelphia and State of Pennsylvania, have invented a new, original, and ornamental Design for an Artificial-Light Shade, of which the following is a specification, reference being had to the accompanying drawing.

In said drawing Figure 1 is a view in side

elevation and Fig. 2 a top or plan view of an artificial light shade or ball showing my new design.

I claim as my invention:

The ornamental design for an artificial light shade, as shown.

KRAFT BOOTH.
